[57] **CLAIM**

The ornamental design for a ring having lockets mounted within its central finger opening, as shown and described.

DESCRIPTION

FIG. 1 is an exploded perspective view of a ring having lockets mounted within its central finger opening showing my new design;

FIG. 2 is a side elevational view showing the lockets mounted in the finger opening of the ring;

FIG. 3 is a front elevational view showing the lockets mounted inside the finger opening of the ring;

FIG. 4 is a left elevational view showing the lockets mounted within the finger opening of the ring;

FIG. 5 is a right elevational view showing the lockets mounted within the finger opening of the ring;

FIG. 6 is a rear elevational view showing the lockets mounted within the finger opening of the ring; and,

FIG. 7 is a side elevational showing the lockets mounted within the finger opening of the ring.
